UNITED STATES PATENT OFFICE.

IGNATSE WINTER, OF WELLAND, ONTARIO, CANADA.

AUTOMOBILE HEAD LAMP.

Application filed August 1, 1928. Serial No. 296,701.

This invention relates to automobile head-lights and has special reference to an automobile headlight having a movable hood or shield.

5 One important object of the invention is to improve the general construction of shielded headlights.

A second important object of the invention is to provide an improved operating 10 means for the shields of such headlights.

A third important object of the invention is to provide a quick acting connection between the shield of such a headlight and the operating means proper.

15 With the above and other objects in view as will be hereinafter apparent, the invention consists in general of certain novel details of construction and combinations of parts hereinafter fully described, illustrated in 20 the accompanying drawings and specifically claimed.

In the accompanying drawings like characters of reference indicate like parts in the several views, and:

25 Figure 1 is a front view of a headlight constructed in accordance with this invention.

Figure 2 is a section on the line 2—2 of Figure 1.

Figure 3 is a section on the line 3—3 of Figure 1.

30 Figure 4 is a section on the line 4—4 of Figure 1.

Figure 5 is a face view of the lens removed from the headlight body.

35 Figure 6 is a face view of the reflector used herewith.

In the embodiment of the invention here shown there is provided a headlight body or casing 10 which may be of any preferred form but for convenience is here shown as 40 hemispherical. Fitted in this body is the reflector 11 and the upper half of the rim 12 of this reflector is cut away as indicated at 13 so that a semi-circular slot 14 is left between the reflector and the body or housing 10. In front of this reflector is the usual 45 lens glass 15 which likewise has its upper portion cut away as at 16 to provide a continuation of the slot 14. This lens is held in position by the usual ring 17. The reflector is also equipped with the lamp 18 and socket 19 in the usual manner. Mounted on the pivot 20 and shaft 21 is an orange peel 50 segment 22 of opaque material, the pivot and shaft being so aligned that the segment 22

swings through the slot 14 from housed position within the casing 10 as shown by dotted lines in Figure 3 and the projected position shown by full lines in the figure and in the other figures. On the outside of the housing is a casing 23 into which the shaft 21 projects and on the end of this shaft is a rock arm 24. The casing 23 has a segmental slot 25 in one side and through this slot extends a lever 26 which is pivoted within the casing 23 intermediate its ends on a pivot 27 so that the lever is provided with a short arm within the casing and a longer arm projecting therefrom. This lever has its short arm connected to the extremity of the rock arm 24 by a C spring 28 of the compression type. The rock arm 24 moves between stops 29, while the lever 26 also moves between stops 30. Now considering Figure 4 for the operation of this part of the mechanism when the lever 26 is rocked in a clockwise direction then the spring 28 will compress until its point of attachment with the lever 26 passes below the line connecting the point of attachment of the spring with the arm 24 and the axis of the pivot 27. When this happens the arm 24 will snap upwardly by the expansion of the spring and the orange peel segment 22 will be quickly retracted into the casing 10 and upon moving the lever 26 back to the position shown in Figure 4 then reverse action will take place.

The lamp bracket used herewith has a hollow cylindrical base 31 from which extends a hollow shaft 32 carrying brackets 33 which are secured to the body or casing 10. Through the hollow arm 32 extends the rock shaft 34 which is provided with a rock arm 35 connected by a link 36 with the lever 26. Within the hollow base 31 the shaft 34 is provided with a double armed lever 37 and from the ends of the lever 37 cords or chains 38 extend to a position convenient to the driver of the machine for pulling the lever in one direction and the other so that the rock arm 35 may be rocked up from the position shown in Figure 4 to retract the orange peel segment or may be rocked down as shown in that figure to protract said segment.

There has thus been provided a simple and efficient device of the kind described and for the purpose specified.

It is obvious that minor changes may be made in the form and construction of the invention without departing from the material

spirit thereof. It is not, therefore, desired to confine the invention to the exact form herein shown and described, but it is desired to include all such as properly come within 5 the scope claimed.

Having thus described the invention, what is claimed as new, is:

In a headlight, a lamp housing, a reflector therein, a lens covering the front of said reflector, said lens and reflector having peripheral cut away portions to provide an arcuate slot between the housing and the lens and reflector, an orange peel segment having its ends pivoted within the housing and movable 10 between retracted and protracted positions through said slot, the pivot at one end constituting a shaft, a rock arm fixed on said

shaft, stops limiting the movement of the rock arm, a lever pivoted intermediate its ends adjacent said shaft and having one arm movable from one side to the other of the shaft beyond the limits of movement of the rock arm, a compression spring connecting the lever arm and the rock arm, a rock shaft extending parallel to the pivotal axis of the segment, a rock arm on said rock shaft, a link connecting the last mentioned rock arm and the lever, a two armed lever fixed to said rock shaft intermediate its ends, and pull cords attached to the arms of the last mentioned lever for controlling said lever from a remote point. 20 25 30

In testimony whereof I affix my signature.
IGNATSE WINTER.
